(57) **CLAIM**

The ornamental design for seats, as shown and described.

DESCRIPTION

FIG. 1 is a top perspective view of a first embodiment of a design for a seat, at a standing position;

FIG. 2 is a top perspective view of the seat shown in FIG. 1, at its most reclined position;

FIG. 3 is a bottom perspective view of the seat shown in FIG. 1, at the standing position;

FIG. 4 is a bottom perspective view of the seat shown in FIG. 1, at the most reclined position;

FIG. 5 is a front elevational view of the seat shown in FIG. 1, at the standing position;

FIG. 6 is a front elevational view of the seat shown in FIG. 1, at the most reclined position;

FIG. 7 is a rear elevational view of the seat shown in FIG. 1, at the standing position;

FIG. 8 is a rear elevational view of the seat shown in FIG. 1, at the most reclined position;

FIG. 9 is a left side elevational view of the seat shown in FIG. 1, at the standing position; the right side elevational view being a mirror image;

FIG. 10 is a left side elevational view of the seat shown in FIG. 1, at the most reclined position; the right side elevational view being a mirror image;

FIG. 11 is a top plan view of the seat shown in FIG. 1, at the standing position;

FIG. 12 is a top plan view of the seat shown in FIG. 1, at the most reclined position;

FIG. 13 is a bottom plan view of the seat shown in FIG. 1, at the standing position;

FIG. 14 is a bottom plan view of the seat shown in FIG. 1, at the most reclined position;

FIG. 15 is a top perspective view of a second embodiment of a design for a seat, at a standing position;

FIG. 16 is a top perspective view of the seat shown in FIG. 15, at its most reclined position;

FIG. 17 is a bottom perspective view of the seat shown in FIG. 15, at the standing position;

FIG. 18 is a bottom perspective view of the seat shown in FIG. 15, at the most reclined position;

FIG. 19 is a front elevational view of the seat shown in FIG. 15, at the standing position;

FIG. 20 is a front elevational view of the seat shown in FIG. 15, at the most reclined position;

FIG. 21 is a rear elevational view of the seat shown in FIG. 15, at the standing position;

FIG. 22 is a rear elevational view of the seat shown in FIG. 15, at the most reclined position;

FIG. 23 is a left side elevational view of the seat shown in FIG. 15, at the standing position; the right side elevational view being a mirror image;

FIG. 24 is a left side elevational view of a design for the seat shown in FIG. 15, at the most reclined position; the right side elevational view being a mirror image;

(Continued)

FIG. 25 is a top plan view of the seat shown in FIG. 15, at the standing position;

FIG. 26 is a top plan view of the seat shown in FIG. 15, at the most reclined position;

FIG. 27 is a bottom plan view of the seat shown in FIG. 15, at the standing position; and,

FIG. 28 is a bottom plan view of the seat shown in FIG. 15, at the most reclined position.
